UNITED STATES PATENT OFFICE

149,855

DESIGN FOR A CHAIR END STANDARD

Willard H. Bond, Jr., Grand Rapids, Mich., assignor to American Seating Company, Grand Rapids, Mich., a corporation of New Jersey

Application January 30, 1947, Serial No. 136,525

Term of patent 14 years

(Cl. D15—8)

To all whom it may concern:

Be it known that I, Willard H. Bond, Jr., a citizen of the United States, residing at Grand Rapids, in the county of Kent and State of Michigan, have invented a new, original, and ornamental Design for a Chair End Standard, of which the following is a specification, reference being had to the accompanying drawing, forming a part thereof.

Figure 1 is a side elevational view of a chair end standard showing my new design;

Figure 2 is a front elevational view of the same;

Figure 3 is a section taken on line 3—3 of Figure 1; and

Figure 4 is a section taken on line 4—4 of Figure 1.

I claim:
The ornamental design for a chair end standard, substantially as shown.

WILLARD H. BOND, JR.
